Edwards & Chamberlain & to Thomas Clegg. Richmond. Maine
Letters, Patent.

The Schedule referred to in the Letters Patent and making part of the same containing a description in the words of the inventors R. Chamberlain and Thomas Clegg themselves of their improvement in pressing Hay, Cotton, &c.

To all to whom these presents shall come. Be it known that Edwards & Chamberlain and Thomas Clegg of Richmond in the County of Lincoln and State of Maine, have invented a new and useful improvement in the press for Hay, Cotton, and other materials and for lifting burdens, and that the following is a full and exact description of the construction and operation of the said machine as invented or improved by us.

Reference being made to accompanying drawings. Fig 1. represents the machine as in action for pressing Hay, Cotton, Stays, or any other material which it may be desirable to compress into a small compass. A.B.C. is the frame work which may be made of any required size, say twenty, four feet long five and a half high and three or four feet wide. B.B represents the brace into which the Hay or other substance is put in the usual way. Then is a board at one end so that one may be filled while the other is pressing. C.C. are the pistons. D. is the wheel to which is applied the power either by crank or by ropes when horses are used. E is a pinion on the shaft of D and moves with it. F is a large cog wheel which mesh is into the teeth of the pinion E. G is the shaft of F. around this shaft passes a strong chain H.H. which also passes over pulleys or pullets in each end of the piston rod at J.J. and is made fast to a strong gear below at K. - Fig 2. represents the power or combination of power, dissolved of the frame work. Fig 3. represents the application of the same power to the lifting of stumps or other heavy burdens. Mode of operation. In order to use our machine as a press, take off the top of the brace, B.B and stow the substance to be pressed, beating it down hard. When thus filled replace the top & keep it down solid by the large bars running in between it and the top beams of the frame, then apply the power at D. The bands &c are disposed in the box in the usual mode of pressing such substances. For lifting Stumps or other burdens. We have a moveable pulley or tackle which we hook on to the stump or burden and the chain H.H. instead of passing this over the pulleys J.J. on the piston, pass this the tackle on the stump and the end of the chain instead of being fastened below to the beam at K. is fastened to a similar beam above. Claims. That we will

especially claims as our invention and for which we request an exclusive right is
1. The application of the pulley as used by us, for a single or double press, over other words
the mode in which to apply and run the chain as above described. 2. The application
and use of our machine to the saving of stamps or other heavy burdens. In testimony
that the above is a true specification of our improvement as above described we have
here set our hands this twenty third day of October in the year of our Lord 1835.
